UNITED STATES PATENT OFFICE.

ROBERT R. WEAVER, OF COLUMBUS, OHIO, ASSIGNOR TO THE RALSTON STEEL CAR COMPANY, OF COLUMBUS, OHIO.

DROP-DOOR-OPERATING MECHANISM.

1,170,128.

Specification of Letters Patent.

Patented Feb. 1, 1916.

Application filed May 20, 1915. Serial No. 29,384.

To all whom it may concern:

Be it known that I, ROBERT R. WEAVER, a citizen of the United States, and a resident of Columbus, in the county of Franklin and State of Ohio, have invented certain new and useful Improvements in Drop-Door-Operating Mechanism; and I do hereby declare the following to be a full, clear, and exact description of the invention, such 10 as will enable others skilled in the art to which it appertains to make and use the same.

This invention relates to improvements in drop door operating mechanism for dumping cars of that type embodying hopper bottoms,—one object of the present invention being to improve and simplify the construction disclosed in Patent No. 1,124,188 granted to me on the fifth day of January, 20 1915.

A further object is to so construct door operating mechanism as to insure maximum lifting power and to eliminate the necessity for locks and pawls.

With these and other objects in view, the invention consists in certain novel features of construction and combinations of parts as hereinafter set forth and pointed out in the claims.

In the accompanying drawings; Figure 1 is a fragmentary plan view showing a portion of a hopper bottom car and illustrating the application of my improvements; Fig. 2 is a view in side elevation with portions of the hopper-body removed and portions in section on the line 2—2 of Fig. 1; Fig. 3 is a view on the line 3—3 of Fig. 1; Fig. 4 is an enlarged view of the central portion of the worm segment showing the clutch devices between said segment and the shaft 9, the latter being shown in section; Fig. 5 is a sectional view of the structure shown in Fig. 4, with the shaft 9 in elevation and mounted in the bearing bracket 7; Fig. 6 is a face view of the clutch member carried by the shaft 9; Fig. 7 is a detail view of the link 14; Fig. 8 is a detail view of the link 15, and Fig. 9 is a detail view of the cross head 10^a.

1, 1 represent the side sills of a car under-frame, and 2 indicates a portion of the centrally located hopper body, the opening in the bottom of the latter being closed by doors 3 hinged at the sides of said opening 55 similar to the construction shown in my

former patent above referred to. The draft sills 1^a of the car terminate at their inner ends at the hopper body and are rigidly secured thereto in any suitable manner.

The operating mechanisms for the doors 60 are supported (for the most part) by and between the draft sills in proximity to the ends of the hopper body,—said mechanisms being duplicated (except as hereinafter explained) at respective ends of said hopper 65 body.

Links 4, 4 are suspended from brackets 5 secured to the draft beams at respective ends of the lower portion of the body 2, and the links at one end of the hopper bottom are connected with those at the other end, by rods or bars 6 disposed under the doors, and on these rods or bars, rollers 10 are mounted so as to run on suitable trackways on the doors, as shown and described 75 in my patent hereinbefore referred to.

Near each end of the hopper body, two brackets 7, 8 spaced apart, are secured between the draft sills and depend therefrom. Shafts 9 are mounted in bearings provided 80 in the brackets 7, 8 of the respective pairs.

A cross head 10^a is secured upon an angular portion of each shaft 9, and the arms 11, 12 of this cross head are disposed at an obtuse angle to each other. The arm 11 is 85 provided at its free end with a lateral enlargement 13, to which one end of a curved link 14 is pivotally attached,—the other end of said curved link being bent laterally and pivotally connected with the depending link 90 4 farthest removed from the arm 11 of the cross head. A curved link 15 is pivotally connected at one end with the arm 12 of cross head 10^a and at the other end said link 15 is made with a lateral bifurcated enlargement 95 15^a pivotally attached to the depending link farthest removed from the arm 12 of the cross head.

A worm segment 16 is loosely mounted upon each shaft 9 and the hub of this segment is made with a clutch member 17 having a lug 18. Another clutch member 19 is secured to each shaft 9 and made with a lug 20 to coöperate with the lug 18 of clutch member 17, and the lugs on the two clutch 100 members are so proportioned as to permit of relative movements of the segment 16 and shaft 9.

Worms 21 are mounted between the draft sills near respective ends of the hopper body, 110

and are disposed over and in mesh with the worm segments 16. A transverse shaft 22 passes through one of said worms for rotating the same, and this shaft is mounted near its ends in bearings 23 secured to the side sills 1, the ends of said shaft being made to project beyond the side sills for the reception of a suitable device for manually operating it. A transverse shaft 24 is connected 10 with the worm 21 at the other end of the hopper body and extends to one side only of the car, where it is mounted in a suitable bearing 25 secured to one of the side sills 1, and projects somewhat beyond the same for 15 the reception of a suitable hand operated device. Sprocket wheels 27, 28 are secured to the shafts 22 and 24 (preferably near their mountings in one of the side sills,) and these sprockets are connected by a sprocket chain 20 29, so that when one or the other of said shafts is rotated, motion will be imparted to both worms 21, for turning the worm segments 16. When the doors are closed, their retention in such position will be insured by 25 the worm gearing, without necessity for the use of pawl and ratchet devices, such as heretofore employed.

Motion imparted to the worm segments by the operation of one of the shafts 22-24, 30 as above explained, will be transmitted through the clutch member 17-19 to the shafts 9. When the shafts 9 shall have been moved sufficiently to overcome the dead centers of the link mechanisms, the weight of 35 the load in the hopper body will force the doors fully open. During the opening movements of the doors, the lugs on the clutch members on the shafts 9 will travel through the space separating the ends of the lugs 40 on the hubs of the worm segments, and thus the opening movement of the doors after the initial operation of the worm gearing will be independent of the latter. To effect the closing of the doors, the trainman will operate one of the shafts 22 or 24 to impart motion 45 to the worms 21 and cause the latter to operate the worm segments 16. Motion will now be imparted by the worm segments to the shafts 9 (through the medium of the 50 clutch devices) and the rotation of said shafts 9 will operate the link mechanisms to close the doors as will be readily understood.

The improved construction of worm gear operating mechanism, located in line with 55 the longitudinal axis of the car at respective ends of the hopper and operated from the sides of the car, is exceedingly simple and provides powerful means for effecting the closing of the doors, with the expenditure 60 of a minimum amount of energy, and also provides efficient means for locking the doors in closed position.

Slight changes might be made in the de-

tails of construction of my invention without departing from the spirit thereof or 65 limiting its scope and hence I do not wish to restrict myself to the precise details herein set forth.

Having fully described my invention what I claim as new and desire to secure by 70 Letters-Patent, is:—

1. The combination with a car under-frame, a hopper body having a single opening in its bottom and draft sills terminating at the hopper body, of two doors closing 75 said single opening, a shaft parallel with the longitudinal axis of the underframe, bearing brackets for said shaft supported by the draft sills, pivoted link mechanism connecting said shaft with the two doors, a 80 worm gear on said shaft, a transverse worm mounted between the draft sill and meshing with said worm gear, and means for manually operating said worm.

2. The combination with a car under-frame, a hopper body having a single unobstructed bottom opening, and drop doors co-operating to close said bottom opening, of a shaft supported by the under-frame parallel with the longitudinal axis thereof and 90 outside of the hopper body, pivoted link mechanism connecting said shaft with the drop doors, a worm gear loose on said shaft, lost-motion clutch devices between said worm gear and shaft, a worm mounted transversely 95 over the longitudinal center of the under-frame and meshing with said worm gear, and means for operating said worm from the sides of the car.

3. The combination with a car under-frame, a hopper body having a single unobstructed bottom opening, two drop doors co-operating to close said bottom opening, and pivoted link mechanism located near respective ends of the hopper body and co-operative with said drop doors, of draft sills terminating at the hopper body, brackets depending from said center sills beyond respective ends of the hopper body, shafts mounted in said brackets, centrally located 100 worm gears mounted on said shafts, means connecting the respective worm gears with the respective link mechanisms, two centrally located transverse worms supported by said draft sills and meshing with the worm gears, manually operable transverse shafts for operating said worms, and sprocket gearing connecting said shafts.

In testimony whereof, I have signed this specification in the presence of two subscribing witnesses.

ROBERT R. WEAVER.
